[57] **CLAIM**

The ornamental design for an element of an outsole, as shown and described.

DESCRIPTION

FIG. 1 is a left side elevational view of an element of a shoe outsole showing my new design;

FIG. 2 is a bottom plan view thereof;

FIG. 3 is a right side elevational view thereof;

FIG. 4 is a front elevational view thereof; and

FIG. 5 is a rear elevational view thereof.

The broken line showing of a shoe midsole is for environmental purposes only and forms no part of the claimed design.

Fig. 1.

Fig. 2.

Fig. 3.

Fig. 4.

Fig. 5.
